UNITED STATES PATENT OFFICE

JOHN F. MACINDOE, OF PHILADELPHIA, PENNSYLVANIA

WATER-PUMP LUBRICATOR

Application filed March 2, 1925, Serial No. 12,538. Renewed February 25, 1930.

This invention relates to grease cups or lubricators from which the lubricant is automatically ejected by means of pressure applied thereto, and which are particularly applicable for use on the bearings of water pumps of the type used on motor cars and trucks, or such types of power units, wherein a water pump and radiator are used for cooling water, in connection with internal combustion engines or motors.

The invention is a modification or improvement on the grease cups or lubricators shown in Letters Patent of the United States, #1,283,841 dated November 5th, 1918, and #1,353,171 dated September 21st, 1920, heretofore issued to the inventor, the said John F. MacIndoe.

The present inefficient methods of lubricating water pumps, employing plain compression cups and grease gun fitting on the pump bearings, are detrimental to the motor, because of the neglect in operating the cup or gun at sufficient intervals to maintain a proper film, or at times operating without the knowledge or ability to ascertain the amount of lubricant required to form a proper film, whereby an excess of lubricant is forced into the system, causing a loss in cooling surface, proportionate to the amount of surface coated by the lubricant which is a non-conductor.

With the grease gun method, the use of the proper and specific water pump lubricant, the density of which in the original state makes it difficult to discharge the lubricant into the bearing unless a high pressure gun is used, induces a tendency to use ordinary and softer densities of grease, many of which are unsuitable for this class of lubrication. Again, to avoid possible mixture of unsuitable greases with proper lubricant, by using the same gun, it would require a separate gun for water pump lubricant and this represents an unnecessary and additional expense not needed where the present device is used.

The objects of my invention are to eliminate or reduce to a great extent the neglect to maintain a proper film of lubricant in the bearings, always present when the hand or intermittent applications are used.

To encourage the use of proper lubricants.

To maintain the film for the entire content of the lubricator instead of the small amount possible to be put in by manual or gun methods. To insure proper and continuous lubrication for upwards of 1500 miles 55 a filling, as developed in actual service, instead of a breakdown of film at few mile intervals, as with the manually operated means.

To provide means to maintain the film 60 while the motor is operating, as compared with the previous means of forming the film when the car or truck is stopped, and the immediate reduction and elimination of the film after a few miles run.

The present device provides a valve to close the outlet orifice when the cup is emptied of the content, preventing the loss of water through the cup, and protecting the leather washer from shrivelling when subjected to 70 the water temperature, such as prevail in normal operating conditions. This valve is of a simple and sturdy construction, and is closed by the main plunger spring, being a part of the plunger construction, unlike the 75 usual ball and spring extensions to ordinary cups, wherein a weak spring, small in size, is used and which is not generally effective or satisfactory.

By preventing water leakage my invention 80 permits a full volume of water to be maintained.

The plunger stem may be of one piece construction, or of a plurality of pieces. If of a plurality of pieces they must work in unison.

Due to the heavy density of water pump lubricants the proper working of the lubricator is best effected by providing an allowance of pressure to conform to the reduction in density of the lubricant due to the average temperature of the circulating water, or approximately, 170 degrees Fah., the claimed point of efficiency.

These and other advantageous ends I attain in the manner hereinafter set forth, reference being had to the accompanying drawings, in which:—

Figure 1 is a vertical perspective view of the assembled lubricator;

Figure 2 is a vertical sectional view on line 2—2 of Fig. 1;

Figure 3 is a transverse sectional view on line 3—3 of Fig. 2; and

Figure 4 is a fragmentary vertical view of the cup illustrating a modification in the venting means.

Referring to the drawings in detail, wherein like reference numbers refer to like parts in all the views, 10 represents the shell or cap of the usual type of grease cup, adapted to receive the cup body 13. 10^a designates an off-centre lock which engages a plurality of catches 13^a to secure the body 13 to the shell or cover 10.

10^b represent vents extending to spring space in cover 10 to provide an exit for any lubricant trapped above the metal plunger washer 14, or in the space provided for the 20 spring 11 to nest when fully compressed.

A spiral compression spring 11 is positioned around the main plunger stem 12 and is adapted for compression between the upper inner portion of the cover or shell 10 and the 25 metal washer 14.

14 is the top metal plunger washer and it shoulders against stem 12 at point 12^g; an opening in the washer permitting it to pass over the stem 12, said stem 12 being reduced in 30 diameter at the point 12^a for such purpose and to form said shoulder.

15 is a leather washer interposed between the top metal washer 14 and a bottom metal washer 16. The said metal washer 16 is slotted (Fig. 3) to fit over a further reduced in 35 diameter portion 12^b of stem 12. The said stem 12 is then increased in diameter to correspond with the portion 12^a to hold the assembled washers 14, 15 and 16 in position.

40 The portion 12^a of stem 12 may be extended downwardly sufficiently so that when the plunger has completed its stroke the valve 13^b, which is shown as conical or tapering in form, reaches and closes the tapering outlet 12^c, which is the valve seat or outlet to the discharge 13^f.

13^e designates the controlling edge of the valve 13^b in the shank.

12^e is the control valve stem which is illustrated as integral with the control valve 13^b. The said control valve stem 12^e terminates in a control plug member of valve 12^d, having the upper controlling edge 12ⁱ and the lower controlling edge 12^h.

55 13^e is the hexagonal portion of the shank body 13, said shank body 13 terminating in an exteriorly threaded portion 13^d to secure the lubricator to the bearing to be lubricated. Said shank has the valve controlled outlet or discharge 13^f therein for the discharge of the lubricant to the bearing.

The stem 12 is shown with integral control stems but may be made sectional for interchangeable control stems for varying densities of grease where it is not desired to change

springs. Standard springs will control three densities of grease according to bearing conditions.

In Fig. 4 I have illustrated a modification of the venting means, utilizing what is known as a hooded vent. The cover or shell 10 is slit and the upper portion thereof is raised like a corrugation, say one-eighth inch above the surface of the shell 10. This forms an opening, 10^e, half moon in form, pointing 70 downwardly.

75 I do not desire to restrict myself as to the precise venting methods illustrated. The vent or vents may be placed anywhere in the cup 10. I have illustrated specific venting 80 means in conjunction with the locking means so that the vents and locking means may be formed at a single stroke of the forming press, or they may be cast together, or they 85 may be positioned independent of the locking means.

A vent or vents may be made on each side of the cover 10, or there may be as many vents made in the cover 10 as may be required for properly venting the cup for the 90 purpose stated. When made as a part of the locking means it will allow the catch bead of the catches 13^a to ride up in a vertical line and reduces the danger of cover unlocking as with the present type where an excessive 95 downward thrust will cause the cover 10 to twist on the angle and unlock, causing loss of cover.

100 *Operation:*—The body portion 13 of the lubricator is filled with lubricant and inserted into the shell 10 and locked in place by means of the bayonet lock 10^a engaging the catches 13^a. This bayonet lock may be made a part of a pair of vents or pressure reliefs 10^b communicating from spring space in cover or shell 10 where the grease may be jammed and preventing the locking of said cover, or the cup may be vented in any other suitable manner.

105 As the body 13 is locked in the shell 10 the spring 11 is compressed between the inner upper portion of the cup 10 and the washer 14 and the plug member 12^d on the stem is drawn to its uppermost position. The lubricant will flow at once, the plug member 12^d holding the flow to a minimum area until the upper edge 12ⁱ of said plug member 12^d passes down beyond the lower portion of the taper 12^c. The increased area then begins and from this point on is the maximum for the balance of the stroke. A tapered shank outlet, with valve shut off, may be utilized if it is desired to use soft greases, in which case the discharge outlet would gradually increase in diameter as the plug member 12^d descended.

110 120 In the present invention I do not use the tapered shank as shown in my previous patents cited, but use a straight shank outlet 12^c with the plug valve 12^d similar to the plug valve illustrated in my Patent 125 130

#1,283,841 cited, in order that as soon as the said plug valve passes the narrowest straight edge outlet the area is immediately expanded to its maximum extent. This is necessary with all heavy lubricants in a device of the size required for this work.

As soon as the plug member 12^a has descended, emptying the cup, the valve 13^b reaches and closes the outlet 12^c, which is the valve seat and the outlet to the discharge 13^d.

The assembled washers 14, 15 and 16 form the plunger. The valve 13^b is shown as conical in form but may be of any suitable design and may be located either at the top or at the bottom of the shank outlet.

From the foregoing description, taken in connection with the accompanying drawings, the advantage of the construction and operation of the device shown will be readily understood by those skilled in the art to which the invention pertains, and while I have described the principle of operation, together with the device which I now consider to be the best embodiment thereof, I desire to have it understood that the device shown is merely illustrative and that such changes may be made as are within the scope of the appended claims.

Having thus described my invention what I claim as new and desire to secure by Letters Patent is:—

1. A lubricator for fluid pumps comprising a lubricant receptacle provided with an outlet, a piston in said receptacle, a spring pressing said piston towards said outlet to discharge lubricant therethrough, a valve stem connected to said piston and projecting through said outlet, a plug valve on said stem arranged to enter said outlet when said piston is in its position corresponding to filled condition of said receptacle, and a closure valve for said outlet mounted on said stem and so spaced with respect to said plug valve as to close said outlet before the discharge stroke of said piston is completed whereby a body of lubricant is always trapped between said piston and said outlet to protect said piston from direct contact with heat and water.

2. A lubricator for fluid pumps comprising a lubricant receptacle provided with an outlet, a piston in said receptacle, a spring pressing said piston towards said outlet to discharge lubricant therethrough, a valve stem connected to said piston, and a closure valve on said stem so located as to close said outlet before the discharge stroke of said piston is completed, whereby a body of lubricant is always trapped between said piston and said outlet to protect said piston from direct contact with heat and water.

In testimony whereof I affix my signature.

JOHN F. MACINDOE.
